BRIDGE EXTENSION FOR EYEGLASSES

Toni Holloway, 73—465 Feather Trail,
Palm Desert, Calif. 92260

Filed Oct. 2, 1969, Ser. No. 19,384

Term of patent 7 years

Int. Cl. D16—08

U.S. Cl. D57—1

FIG. 1

FIG. 2

FIG. 3

FIG. 4

FIG. 1 is a perspective view of a bridge extension for eye glasses embodying my new design;

FIG. 2 is a front elevational view thereof on an enlarged scale;

FIG. 3 is a side elevational view thereof on an enlarged scale; and

FIG. 4 is a top view thereof on an enlarged scale.

The eyeglasses are shown in broken line in FIG. 1 for illustrative purposes only.

I claim:

The ornamental design for a bridge extension for eyeglasses, as shown and described.
